UNITED STATES PATENT OFFICE.

FRANCIS P. CHANDLER, OF HOUSTON, TEXAS.

TOY.

Application filed October 30, 1922. Serial No. 597,735.

To all whom it may concern:

Be it known that I, FRANCIS P. CHANDLER, a citizen of the United States, residing at Houston, in the county of Harris and State of Texas, have invented certain new and useful Improvements in Toys, of which the following is a specification.

This invention relates to new and useful improvements in a toy.

10 One object of the invention is to provide a toy of the character described which is preferably mounted on wheels and is composed of a frame work and removable translucent side walls which bear the representations 60 of animals or other figures which are revealed by means of a light enclosed within the frame work.

Another object of the invention is to provide a device of the character described 20 composed of a frame work having removable interchangeable translucent side walls which bear representations of animals or figures, said characters being revealed by a light within the frame work and said frame work 65 being constructed, if desired, in tiers one above the other.

Another object of the invention is to provide a toy which is attractive in appearance and which may be cheaply and easily constructed and which will be durable in use.

With the above and other objects in view the invention has particular relation to certain novel features of construction, arrangement of parts, and use, an example of which 70 is given in this specification and illustrated in the accompanying drawings, wherein:—

Figure 1 shows a perspective view of the device.

Figure 2 shows a fragmentary plan view 40 thereof partially in section.

Figure 3 shows an end view partially in section.

Figure 4 shows a side view of one of the wall panels broken away and,

45 Figure 5 shows an end view thereof partially in section.

In the drawings the numeral 1 designates a platform which is mounted on the axles 2, 2 which in turn are supported by the carrier wheels 3.

50 Mounted on the platform are the corner posts 4 which are secured in place by means of the rod 5 which are fitted alongside through said posts and whose lower ends are fitted through the platform and are secured thereto by means of the nut 6. The outer sides are shouldered in and an angle

iron 7 is secured thereto, said shouldered in portion forming with said angle iron the vertical grooves 8, 8. The walls are formed of panels consisting of the rectangular framework 9 and the fabric covering 10. These panels are fitted into the respective grooves 8 at their ends and are thus held in place. Representations of animals or other figures 11 are painted on the panels and within the structure there is a candle 12 which is held in place by a bracket 13 mounted on the platform 1. The light from the candle reveals the representations on said panels. A number of panels may be used 65 and interchanged so as to give a variety of effects. As shown in Figure 2 the frame work is built in two tiers, the upper tier being of substantially the same structure as the lower. It is obvious of course that additional tiers may be added as desired.

70 What I claim is:—

1. A device of the character described including a platform mounted on suitable carrier wheels, corner posts mounted on the 80 platform, a rod fitted lengthwise through each post, whose lower ends extend through the platform and are secured thereto, the outer sides of said posts being shouldered in an angle iron, so secured to each post that 85 said shouldered in portions will form with the wings of said angle iron vertical grooves, panels forming walls, the respective ends of said panels being fitted into said grooves, the said panels consisting of rectangular 90 framework and translucent material secured to said frame-work, a bracket mounted on said platform and forming a candle holder.

2. A device of the character described including a platform mounted on suitable carrier wheels, corner posts mounted on the platform, a rod fitted lengthwise through each post, whose lower ends extend through the platform and are secured thereto, the outer sides of said posts being shouldered in 95 an angle iron, so secured to each post that said shouldered in portions will form with the wings of said angle iron vertical grooves, panels forming walls, the respective ends of said panels being fitted into said grooves, 100 the said panels consisting of rectangular framework and translucent material secured to said frame-work, a bracket mounted on said platform and forming a candle holder, a rectangular frame mounted on the top of 110 said posts and secured thereto, by said rods, corner posts mounted on said last mentioned

frame having shouldered in sides, angle irons fastened to said last mentioned corner posts whose wings form with said shouldered in portions vertical grooves provided to receive panels of translucent material, and a top platform mounted on said last mentioned posts.

In testimony whereof I have signed my name to this specification in the presence of two subscribing witnesses.

FRANCIS P. CHANDLER.
